HAIR DRYER

Theodore Friedman, Glen Ellyn, Ill., assignor to Sunbeam Corporation, Chicago, Ill., a corporation of Illinois

Filed June 29, 1966, Ser. No. 2,861

Term of patent 14 years

(Cl. D86—10)

Fig. 1.

Fig. 2.

Fig. 3.

Fig. 4.

Fig. 5.

FIG. 1 is a perspective view of a hair dryer showing the novel design;

FIG. 2 is a top plan view of the hair dryer;

FIG. 3 is an end elevation view of the hair dryer when viewed from the left hand end of FIG. 1;

FIG. 4 is a rear elevation view of the hair dryer; and

FIG. 5 is a perspective view of the hair dryer in open condition with the bottom and top casing halves being separated.

The dashed line showing inside the top half casing portion represents a hair dryer cap and electric cord stored therein.

I claim:

The ornamental design for a hair dryer, as shown and described.
